JAR LID OPENER

Roy V. Harrold, Columbiana, Ohio

Application July 22, 1935, Serial No. 32,674

1 Claim. (Cl. 81—3.1)

This invention relates to jar holders and openers and has for the primary object the provision of a device of this character which may be readily adapted to a jar and its cap so that a person may 5 easily hold the jar and turn the cap off of said jar without mutilating either and which is simple, durable and efficient and which may be manufactured and sold at a low cost.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a side elevation, partly in section, illustrating a combined jar holder and opener constructed in accordance with my invention and 20 showing the same applied to a jar and its cap.

Figure 2 is a top plan view illustrating the same.

Figure 3 is a bottom plan view partly in section illustrating the same.

25 Referring in detail to the drawing, the numerals 1 and 2 indicate pairs of superimposed arcuately curved jaws, each pair of jaws having integral therewith handles 3. The jaws 2 are equipped with a suitable yieldable covering 4 while the jaws 1 are provided with gripping serrations 5. The jaws 1 are pivotally connected by a pivot 6. The jaws 2 are pivotally connected to one end of a substantially U-shaped bracket 7 which includes parallel arms 8 and a bight portion 9. The bracket 7 is arranged so that the arms 8 30 thereof are disposed in superimposed relation

with the lowermost arm of the shortest length and having the jaws 2 pivoted thereto. A plate or link 10 has one end connected with the pivot 6, while the opposite end of said plate or link is offset, as shown at 11, and pivoted to the long 5 arm 8 of the bracket 7. The jaws 2 are capable of swinging relative to the plate or link 10 and the latter is capable of swinging on the bracket.

In operation, the jaws 2 are applied to a jar 12, as shown in Figure 1, and the jaws 1 are 10 applied to the cap 13 of the jar. The operator grasps the handles of the jaws 2 in one hand and the handles of the jaws 1 in the other hand. The handles of the jaws 1 are then swung away 15 from the handles of the jaws 2, turning or unthreading the cap 13 from the jar 12. The arrangement of the plate or link 10 permits the jaws 1 to remain centered with respect to the jar and cap when turning said cap off of the 20 jar. The same operation is employed for threading the cap 13 on the jar, except that the handles of the jaws 1 are swung in an opposite direction. Through the handles of the jaws 2 the jar 12 25 is held against turning.

Having described the invention, I claim:

A combined jar holder and cap remover comprising a bracket including parallel arms of different lengths integrally connected with each other, a pair of jaws pivoted to one of said arms, 30 a link pivoted to the other arm, a second pair of jaws arranged in superimposed relation to the first pair of jaws, a pivot connecting the second pair of jaws and connecting the link thereto, and handles integral with said jaws. 35

ROY V. HARROLD.
